POCKETBOOK

Max Sachs, Far Rockaway, N. Y.

Application June 15, 1935, Serial No. 26,759

1 Claim. (Cl. 150—29)

This invention relates to new and useful improvements in pocketbooks and more particularly it pertains to devices of this character commonly known as ladies' hand bags.

5 In the usual construction of hand bags of the afore-mentioned type, the bag body is secured to the members of a pivoted frame by engagement of the edges of the open side of the bag body between the side walls of a channeled frame member, the channeled frame member being crimped or compressed to effect the clamping.

It is the object of the present invention to improve the construction of pocketbooks of the afore-mentioned character and so to construct 15 such pocketbooks that the body may be readily removed from the frame without damage to either of the parts.

In pocketbooks constructed as above described, it often happens that the body, through strain 20 and use, becomes disconnected from the frame and renders the bag unsafe for further use, and it is a feature of this invention to provide a new and novel means whereby the body of the pocketbook may be so attached to the frame that said 25 attachment of the body to the frame will be secure and all possibility of the body becoming detached from the frame will be removed.

A further feature of the invention resides in 30 a novel construction which gives a generally neat and pleasing appearance to the finished article.

Other features of the invention will appear as 35 the nature thereof is more clearly understood, and for this purpose, reference will be had to the accompanying drawing, wherein:

Figure 1 is a distended perspective view showing a body and frame disconnected with respect to each other, the pocketbook being constructed in accordance with the present invention,

40 Figure 2 is a transverse detail sectional view on an enlarged scale of a portion of the pocketbook body and frame illustrating one form of the invention, and;

Figure 3 is a similar view illustrating a slight- 45 ly modified form of the invention.

A pocketbook constructed in accordance with the present invention consists of a body portion 10 and a frame 11.

The body portion may be constructed in any 50 desired shape or form, the body being shown comprising side walls 12, foldable end wall 13 and a folding bottom wall 14 all secured together to form the body in the ordinary manner.

In accordance with the present invention, I 55 employ securing bars 15 and these securing bars

15 are attached to the free edges of the side members 12, which free edges form the opening of the pocketbook. The securing bars 15 have a covering 16, which cover is preferably of the same material as that from which the pocketbook is formed in order to match the same, although this is not necessarily so. The securing bars 15 as employed in that form of the invention illustrated in Figures 1 and 2 are provided with perforations 17, the purpose of which will 10 be hereinafter more clearly set forth, and while these securing bars are herewith shown as of substantially semi-circular cross sectional form, it is to be understood that the cross sectional shape of these bars is immaterial and that they 15 may be constructed of any cross sectional shape.

The frame 11 comprises pivoted leg members 18 pivotally connected together as at 20. The leg members 18 are connected by crossbars 21, and these crossbars are provided on one side 20 edge with a flange 22. The legs 18 are connected to the crossbars in such a manner that flanges 23 cooperating with the flanges 22 are provided. The securing bars 15 heretofore described are adapted to be removably secured to 25 the crossbars of the frame and I will now describe the manner in which this is accomplished.

In that form of the invention illustrated in Figures 1 and 2, the crossbars of the frame are provided with screw threaded studs 30 which 30 project outwardly therefrom. These screw threaded studs are rigidly attached to the crossbars of the frame and are arranged in such a manner that they will be received in the openings 17 in the securing bars 15 when the securing 35 bars are placed in position upon the crossbars. To determine the proper position of the securing bars, they are adapted to engage the flanges 22 and the flanges 23 of their respective crossbars 21, and for fastening the securing bars in place 40 upon the crossbars of the frame, members 35 are employed. These members 35 are preferably in the form of ornamental nuts having a threaded socket to receive the studs 30, the nuts in the present instance being shown as of spherical 45 form.

In that form of the invention illustrated in Figure 3, in lieu of the threaded studs 30, the crossbars 21 of the frame are provided with 50 openings 40 which are adapted to receive threaded fastenings 41, herein illustrated as wood screws which have holding engagement with the securing bars 15. These threaded fastenings will be inserted from the inside of the crossbars 21 55

of the frame and will pass into engagement with the securing bars 15 of the pocketbook body.

From the foregoing it will be apparent that when it is desired to remove the body of the pocketbook from the frame, it will only be necessary to remove the ornamental nuts 35 in that form of the invention illustrated in Figures 1 and 2, or the threaded fastenings 41 in that form of the invention illustrated in Figure 3, 10 after which the securing bars may be readily disengaged from the crossbars of the frame. It being understood that the securing bars form a permanent part of the pocketbook body, it will readily be seen that removing of the securing bars 15 from the crossbars of the frame will permit of complete removal of the pocketbook body with respect to the frame, since, as illustrated in the drawing, the pocketbook body and the frame are not attached to each other in any other manner than by the securing bars 15, and that when 20 they are disengaged with respect to the crossbars of the frame, the pocketbook body and frame may be readily separated one from the other. It is also to be noted that this separation of the pocketbook body from the frame can be 25 accomplished without injury or damage to either

member and that the same may be attached to the frame and removed therefrom as often as desired without damage to either member.

While the invention has been herein illustrated in its preferred forms, it is to be understood that it is not to be limited to the specific details of construction herein illustrated and that it may be practiced in other forms without departing from the spirit thereof.

Having thus described the invention, what is 10 claimed as new, is:

A pocketbook construction comprising a two part pivoted frame, a crossbar forming a member of each frame part, flanges defining the edges of each of said crossbars, a bag body, bars carried by said bag body and completely enclosed thereby, said bars being of a size adapted to be received snugly within the flanges of the crossbars of the frame, and means for attaching the bars carried by the bag body to the bag body 20 and the crossbars of the frame, said means comprising a plurality of wood screws passing through material of the body and the crossbars of the frame and having threaded engagement with the bars carried by the bag body.

MAX SACHS.
